UNITED STATES PATENT OFFICE.

ED FULLER, OF ELMER, OKLAHOMA, ASSIGNOR OF ONE-HALF TO AARON A. HOUGHAM, OF ALTUS, OKLAHOMA.

AXLE-BOX FOR LOCOMOTIVE-DRIVERS.

No. 926,862.

Specification of Letters Patent.

Patented July 6, 1909.

Application filed February 5, 1909. Serial No. 476,306.

To all whom it may concern:

Be it known that I, ED FULLER, a citizen of the United States, residing at Elmer, in the county of Jackson and State of Oklahoma, have invented a new and useful Axle-Box for Locomotive-Drivers, of which the following is a specification.

This invention relates to journal boxes of that type especially designed for use in connection with the axles of the driving wheels of locomotives.

The object of the invention is to so improve the construction of devices of this character as to prevent the shoe-adjusting wedges from becoming so tightly seated as to render their removal extremely difficult.

A further object is to provide improved means for adjusting the wedges, said means coöperating with tie-bars of novel form used in connection with the box-carrying hangers of the locomotive frame.

With these and other objects in view the invention consists of certain novel details of construction and combinations of parts hereinafter more fully described and pointed out in the claim.

In the accompanying drawings the preferred form of the invention has been shown.

In said drawings:—Figure 1 is a view partly in elevation and partly in section of the device constituting the present invention. Fig. 2 is a section on line A—B Fig. 1. Fig. 3 is a transverse section through the tie-bar and showing the lower portion of the wedge and its adjusting screw in elevation.

Referring to the figures by characters of reference 1 designates a portion of a locomotive frame and extending downwardly from this frame are hangers 2 and 3, the inner face 40 of hanger 3 being inclined upwardly toward the hanger 2 and constituting a bearing for an adjusting wedge 4 which, as shown especially in Fig. 3, has a groove 5 in one face at the lower end thereof. The upper end of this 45 groove is enlarged as indicated at 6 to receive the round head 7 of an adjusting screw 8.

This screw rests within the groove 5 and the threaded portion thereof extends through and engages a tie-bar 9 having transverse recesses 10 in its upper face into which the lower ends of the hangers 2 and 3 project. Each of these hangers has one or more grooves 11 in one face thereof, the upper ends of the grooves being enlarged as shown 55 at 12 to receive the heads of fastening bolts

13. These bolts extend through the tie-bar 9 and are secured in place by means of nuts as ordinarily. Obviously by tightening the nuts on the bolts 13 the tie-bar 9 can be firmly pressed against the lower ends of the 60 hangers, and a rigid support thus provided for the axle-box.

As shown in Figs. 1 and 2 a lock nut 14 may be mounted on the threaded portion of the bolt 8 so as to bear against the lower face 65 of the tie-bar 9, and, in order to permit this bolt to be readily rotated, the lower end thereof is reduced to form a head 15 so shaped as to be easily engaged by a wrench or other suitable tool for the purpose of turning the 70

Arranged above the tie-bar 9 and between the hangers 2 and 3, are shoes 16, each of which is provided along opposite edges with longitudinal flanges 17. One of the shoes is 75 designed to straddle the hanger 2, while the other shoe embraces the upper portion of the hanger 3 and the wedge 4. These shoes are held against longitudinal displacement by the frame 1 and the tie-bar 9, and arranged 80 to slide between the shoes is a box 18 the sides of which are channeled longitudinally as indicated at 19 to receive the shoes 16. The box 19 has an opening 20 extending therethrough for the reception of the axle 85 and the bottom portion of this opening is formed by a cup 21 which is removably mounted within the bottom portion of the box and extends throughout the length of the opening 20, said cup being held in place 90 by means of transversely extending holding pins 22, which are insertable laterally through the lower portion of the box adjacent the inner and outer faces thereof. The cup 21 is designed to hold waste or other similar material, and, as shown in Fig. 1, a lubricant receptacle 23 may be formed in the upper portion of the box 18 and communicate with the opening 20 through one or more apertures 24.

100 Wedges have heretofore been used in connection with the boxes of driving wheels, but difficulty has been found in unseating them, especially after they have been in frictional engagement with the bearing surfaces for a 105 long period. One of the causes has been the fact that the wedges ordinarily come in direct contact with the box and both the wedge and its bolt thus subjected to considerable strain which often breaks the bolt and results 110

2
in a "stuck" wedge, burned out brass, etc. It has also been difficult to draw the wedge downwardly out of frictional engagement with the bearing surfaces because of the lack 5 of proper connection between the bolt and the wedge. By providing the shoe 16 between the box and the wedge 4 the bolt of the wedge is relieved of all strains and the objectionable features heretofore enumerated are 10 thus entirely overcome. In view of the particular connection employed between the bolt 8 and the wedge 4 said wedge can be shifted upwardly by turning the bolt in one direction, and can be positively drawn downwardly by turning the bolt in the other direction. 15

The present invention can be applied to locomotives now in use without difficulty and at comparatively small cost.

20 Obviously various changes may be made in the construction and arrangement of the parts without departing from the spirit or sacrificing the advantages of the invention.

What is claimed is:—

25 In a device of the class described, a frame, hangers depending therefrom, a tie-bar having grooves constituting seats for the ends

of the hangers, tie-bolts detachably seated within the lower ends of the hangers and extending through the seats and the end portions of the tie-bar for holding the bar and hangers together, a wedge bearing against one of the hangers, said hanger having an inclined face, there being a counter-bored recess within one end of the wedge, an adjusting bolt removably mounted within said recess, said bolt having a head movably mounted in the counterbored portion of the recess, said bolt being screwed into the tie-bar, a shoe embracing the wedge and a portion of the adjoining hanger, a shoe embracing the other hanger, both shoes bearing upon the tie-bar, and a box interposed between the shoes and having seats or grooves in the sides thereof for the reception of the shoes.

In testimony that I claim the foregoing as my own, I have hereto affixed my signature in the presence of two witnesses.

ED FULLER.
